UNITED STATES PATENT OFFICE.

ALBERT G. KOCH AND LOUIS C. FLOTOW, OF APPLETON, WISCONSIN.

CARBURETOR HEATER.

1,407,285.

Specification of Letters Patent. Patented Feb. 21, 1922.

Application filed February 19, 1921. Serial No. 446,207.

To all whom it may concern:

Be it known that we, ALBERT G. KOCH and LOUIS C. FLOTOW, citizens of the United States, residing at Appleton, county of Outagamie, and State of Wisconsin, have invented new and useful Improvements in Carburetor Heaters, of which the following is a specification.

This invention relates to heaters for carburetors designed to aid in the starting and running of a hydrocarbon motor.

Objects of this invention are to provide a heater for a carburetor which may be attached to the carburetor without altering the latter's construction; which may be easily applied; and which will cut down upon the drain upon the starting battery as the starting is greatly facilitated due to the increased volatility of the hydrocarbon when the heater is in operation.

Further objects are to provide a heater for a carburetor so arranged that the amount of heat may be adjusted to suit the demands, as for example, to allow a relatively large amount of heat to be delivered prior to, or at, starting, and a relatively smaller amount to be delivered under other conditions; and to provide such a carburetor heater so arranged that all of the heat in the different adjustments is effective.

Further objects are to provide a carburetor heater in which provision is made for absorbing the moisture due to the sweating of the carburetor; to provide a heater in which radiation is very small; and to provide a heater of simple and sturdy construction which may be cheaply and readily manufactured.

An embodiment of the invention is shown in the accompanying drawings, in which:

Fig. 1 is a diagrammatic view of the heater and circuits and shows a carburetor float chamber in section.

Fig. 2 is an elevation of the carburetor partly in section showing the heater in position.

Fig. 3 is a diagrammatic view showing the circuits and the heating element removed and in extended position.

Fig. 4 is a section on the line 4-4 of Fig. 1.

Fig. 5 is a section on the line 5-5 of Fig. 1 illustrating in detail the construction of one of the contacts of the controlling switch. The carburetor float chamber 1 may be of any of the usual constructions and has wrapped thereabout the heating unit. This

heating unit comprises a heating element formed of a pair of mica strips 2 and 3 which may, if desired, be integrally joined at 4 to aid in maintaining the proper spacing between the strips. About these strips is wound a flat resistance band 5 which may, for example, be of nichrome or similar resistance material. As illustrated in Fig. 3, this resistance strip may be wound continuously from one end of the strip 2 around the mica to the other end of the strip 3. This heating element is enclosed between a pair of mica sheets 6 and 7 to insure proper insulation and protection of the resistance element. This heating element is positioned between a strip of relatively thick fabric 8, which preferably is non-combustible and absorbent and lies next to the float chamber 1, and a strip of fiber paper 9. Outside of this fiber paper 9, a strip of asbestos 10 is positioned. The entire heating unit is protected by an outer casing 11 of tin or other flexible thin metal which is conformed to the contour of the float chamber and may be provided with upper flanges 12 to aid in retaining the heating unit in place. It is clamped around the float chamber by means of a buckle 13 formed upon one projecting strap member integral with the casing 11 and cooperating with the slotted strap member 14 also formed integral with the casing 11.

In this manner the heating unit may be readily placed about the float chamber and locked in position with a minimum expenditure of effort and in a very short space of time. The absorbent insulator 8 which is in contact with the float chamber 1 will absorb any moisture due to the sweating of the carburetor and will prevent such moisture from reaching the electrical resistance elements. When, however, this insulator becomes heated, in the normal operation of the device, the moisture is expelled. This prevents the material from becoming permanently saturated and therefore prevents the moldy condition which would follow if such saturation occurs.

The electrical connections are made with the resistance element by means of binding posts 15, 16 and 17. These binding posts are each provided with a shank 18 which extends through the tin casing and the successive layers and contacts with the resistance element. It is protected by insulating flanged bushing members 19 in the usual manner.

The switch for controlling the operation

of the heating unit comprises a base 20 upon which a metallic arm 21 is pivotally secured at 22. This base also carries a pair of ordinary spring contacts 23 and 24 adapted to contact with the metallic rod 21 when it is swung to opposite ends of its stroke. A third contact, indicated generally at 25, is carried by the base. This contact, as may be seen from reference to Fig. 5, comprises 10 an upper spring arm 26 and a lower spring arm 27 held in separated and insulated relation to each other by an insulating block 28. The metallic arm 21 of the switch is provided with a conducting sleeve 29 located in a position to pass between the upper arm and the lower arm 26 and 27 of this contact and to electrically bridge the gap therebetween. This conducting sleeve is insulated from the metallic arm 21 by means 20 of an insulating sleeve 30.

The electrical connections are as follows. A battery 31 is grounded as indicated at 32 and has its outgoing head 33 connected with the pivot point 22 of the switch. When 25 the switch is in starting position, which would correspond to the right hand dotted line position, this lead is connected by the metallic arm 21, the contact 24, the wire 34 to the binding post 17 which is located 30 centrally of the resistance element. The current now passes from the battery through the lower half of the resistance element (see Fig. 3), to the contact 16 along the wire 35 to the ground 36. A second circuit 35 is simultaneously established and is as follows. From the battery 30, through the lead 33, arm 21, contact 24, conductor 34, contact 17 through the upper half of the resistance element to the binding post 15 along the wire 37, the wire 38 to the lower spring arm 27, of the contact 25, through the conducting sleeve 29 to the upper spring arm 26, along the conductor 39 to the ground 40.

45 It will be seen that when the switch arm is swung to the right, the upper and lower resistance elements are connected in parallel and that the current from the battery passes to the central binding post 17 and there 50 divides, passing through each of the halves of the resistance element and through the ground back to the battery. In this manner, a relatively large generation of heat may be secured whenever it is desired, particularly when starting and in cold weather.

When the motor has started and it is desired to use this heating element in running position, the switch arm 21 is thrown to the left as indicated in dotted lines. This 60 disconnects the upper and lower spring arms 26 and 27 and opens the ground connection for the upper resistance element. The battery is now connected through the lead 33, switch arm 21, contact 23, conductor 38 to

the binding post 15. The current now passes 65 through the resistance element to the binding post 16, through the conductor 35 to the ground 36.

It will be seen that this last arranged means connects the resistance elements in 70 series. It is of course to be understood that the switch arm 21 may occupy a neutral position as indicated in full lines in Figure 1 thereby opening any circuit connecting the 75 battery with the heating element.

It will thus be seen that a series-parallel control of the heating element is provided and that at all times all of the heat generated is effective as none is wasted in auxiliary controlling resistances. It will also 80 be seen that excellent thermal insulation is provided and that mechanical protection is afforded by the encasing tin member 11.

We claim:

1. An electrical heater for a carburetor comprising a heating element, means for positioning said heating element upon said carburetor, and means for connecting said heating element to vary the amount of energy consumed by said element by varying the effective resistance of said heating element.

2. An electrical heater for a carburetor comprising a heating unit composed of a mica strip and a resistance member carried thereby, heat resisting means positioned upon opposite sides of said element, a protecting sheathing enclosing said resistance element and heat resisting means and adapted to engage a portion of the carburetor to position the heating element and heat resisting means thereon.

3. In combination, a carburetor, an electrical heater therefor and an electrical system connected with said heater whereby portions of said heater may be connected in series or in parallel to vary the amount of energy consumed by said heater whereby the overall efficiency is not decreased.

4. As an article of manufacture, a flexible 110 heating unit adapted to be wrapped about a fuel feeding element of an internal combustion engine, said flexible heating unit having an inwardly projecting flange adapted to seat upon said fuel feeding element.

5. In combination, a carburetor, an electrical heater thereon and including heating elements having a plurality of members adapted for connecting conductors, an electrical switch, and conductors connecting said switch and said heating elements, said switch and conductors being adapted to permit variation in the effective resistance of said element.

ALBERT G. KOCH,
LOUIS C. FLOTOW.
